UNITED STATES PATENT OFFICE.

LUTHER STRINE MUNSON, OF LONG BEACH, CALIFORNIA, ASSIGNOR OF ONE-HALF TO
THOMAS J. EVANS, OF LONG BEACH, CALIFORNIA.

NAVAL CONSTRUCTION.

1,249,173.

Specification of Letters Patent.

Patented Dec. 4, 1917.

Application filed October 29, 1917. Serial No. 199,156.

To all whom it may concern:

Be it known that I, LUTHER STRINE MUNSON, a citizen of the United States, residing at Long Beach, in the county of Los Angeles and State of California, have invented certain new and useful Improvements in Naval Construction; and I do hereby declare the following to be a full, clear, and exact description of the invention, such as will enable others skilled in the art to which it appertains to make and use the same.

The principal feature of this invention is the construction of a ship made mostly of wood, and yet strong enough to stand the vibratory motion due to being driven at a high speed by screw propellers, as well as to stand the other strains incident to being driven at a high speed in a seaway.

My invention will be more fully understood after reference to the accompanying drawings, in which:

Figure 1 is a side view showing the central portion of the ship with the planking on, the frames and bracing beneath being shown in dotted lines, just beyond each side of the midship section, fore and aft of which the planking is shown as removed to show the frames and bracing, and the bow and stern are shown as still further broken away to show the longitudinal steel stringers.

Fig. 2 shows in its upper half the deck plan with part of the deck broken away, and the lower half shows a section along the broken line 2—2 of Fig. 3, part of the ceiling of the bottom being broken away to show the parts beneath.

Fig. 3 shows a section along the line 3—3 of Fig. 2, and looking in the direction of the arrows.

Fig. 4 shows a section along the line 4—4 of Fig. 2, and looking in the direction of the arrows.

Fig. 5 shows a section along the line 5—5 of Fig. 4, and looking in the direction of the arrows.

Fig. 6 shows a section through part of the upper deck and the bulwark and adjacent parts.

Fig. 7 shows a section along the line 7—7 of Fig. 6, and looking down.

Fig. 8 is a detail showing in perspective

one of the compound frames used in the construction of the vessel; and

Fig. 9 shows the steel skeleton only of a slightly modified form of construction, parts 55 of the wood being indicated in dotted lines.

1 represents the keel constructed in the usual way, and 1^a the garboard strakes; 2 and 3 represent stem and stern posts constructed in the usual way.

4 represents the main keelson, and 5 and 6 the bilge keels. 7 represents one of the frames, which are secured to the keel and the keelsons, respectively. 8 represents one of the floor beams, which are connected to the frames by the margin plates 8^a. 9 represents the longitudinal bulk head, 10 one of the between deck beams, and 11 represents one of the upper deck beams.

12 represents one of the wooden transverse bulk heads, and 13 represents one of the various angle irons used in the structure. 14 represents diagonal bracing, preferably let into the face of the bulk head, and 15 represents the outer diagonal bracing which rests 75 flush on the face of the bulk head and is bolted thereto and to the diagonal bracing 14. The ends of these braces are connected to angle irons 13, the whole forming a compound lattice girder made of wood and 80 steel, having the strength of the metal combined with the strength and yielding properties of the wood.

Similar diagonal bracing 14 and 15 is applied to both sides of the central fore and aft 85 bulk head 9. Similar diagonal bracing is also provided inside of the outer planking 16; and also on the top of the deck beams 11 and below the deck 17; thus with the fore and aft bulk head and the transverse bulk 90 heads braced as shown, I provide a structure made mainly of wood reinforced vertically, longitudinally and diagonally with steel; the whole forming an extremely strong and resilient cellular structure.

The ends of the transverse bulk heads 12 project into bolsters 12^a (see Fig. 7), which span three or more frames and thus distribute any strain brought on the bulk head over a plurality of frames; also these bolsters afford means for permitting the calking of the joints at the ends of the trans-

verse bulk heads, thus securing a water-tight joint, and more especially taking care of any shearing strains.

In order to still further strengthen the structure, I provide, along the sides of the vessel, a series of longitudinal stringers 18, preferably in the form of T-irons, bolted or riveted to the frames 7 and extending from the stem to the stern post, where their ends are tied together, respectively, by cross plates 19 and 20, as shown in Fig. 2.

Beneath the ends of the deck beams, I provide steel knees 21, in the form of angle irons, riveted to triangular plates, as shown most clearly in Fig. 6.

The frames 7 are preferably of a composite structure of wood and steel, as shown in cross section in Fig. 7, in which 7^a represents a steel bar, T-shaped in cross section, whose web projects into a groove provided in the two wooden timbers 7^b, to which it is connected by the bolts 7^c and 7^d.

The various transverse beams 8, 10 and 11 are of similar construction, having T-irons 11^a projecting into the wooden timbers 11^b, to which they are connected by means of the bolts 11^c, and certain of these bolts project through the deck or planking as shown in Figs. 6, 7 and 8.

The frames are connected to the floor beams 8 by means of the margin plates 8^a and the margin knees 8^b, as also by the keelsons 4, 5 and 6.

22 represents the upper deck; 23 the between deck and 24 the ceiling above the bilge tanks 25, in the upper part of which tanks the horizontal partition 26 is provided, which may be either of wood or of steel plating.

Additional braces 27 may also be provided in the bottom of the ship, as shown in Fig. 3. Suitable hatch combings 28 and 29, see Fig. 3, are provided where needed, which are covered by the hatch covers 30 and 31, respectively. In order to strengthen the structure where it is weakened by cutting away for the hatch, I provide in the hatch combings T-irons 32, to which the diagonal bracing is connected, as shown in Figs. 2 and 3.

In order to further strengthen the structure vertical beams 40 may be provided, as shown in Fig. 9, which beams consist of plates reinforced at their edges with the angle irons 41. These plates are bolted to the stringers 18 by means of angle iron plates, thus forming an exceedingly strong metal structure.

To further strengthen the structure, angle braces 42 and bolts 43 may be provided between the keelsons, as shown in Fig. 9.

As additional strengthening means a shear strap 44 may be provided, extending the length of the ship and connected to the diagonal bracing beneath the upper deck.

The frames 7 may also be provided with 65 strengthening strips 45 abreast the deck 23, 46 opposite the deck 24, and 47 below the keelsons. Furthermore, a metal strip 48 countersunk in the beam 8 may be provided. These strips 45, 46, 47 and 48 enable the 70 corresponding bolts to have a metal bearing for each end.

In assembling the parts the keel is laid in the usual manner, and the lower member of the double bottom set; then the steel T's 75 in the keelsons are set and fastened to the lower member, then the keelson timbers are set and fastened.

The top member of the double bottoms is then set and fastened, the margin plates set 80 and riveted to the top and bottom member of the double floors, and the bilge frames are continued to the decks and longitudinal T's placed.

The longitudinal bulk head is then set up 85 to the between deck level, when the between deck beams are set and fastened and the longitudinal bulk head continued to the upper deck, and the upper deck beams are set and fastened.

The steel lining of the bilge tanks is then set and calked.

The bottom is then planked to above the turn of the bilge. The bilge tanks are completed; the blocking at the ends of the floor beam beneath the margin plate is set and fastened, and the ceiling of the double bottom is now placed so that the transverse bulk heads may be set.

The ceiling of the double bottom is not to 100 be cut for transverse bulk heads, but is to be continuous from end to end, except that the transverse bulk heads are to be rabbeted about one inch into the ceiling. The longitudinal and cross bulk heads are to 105 be calked and painted before the diagonals are set.

All timber is to be surfaced on four sides and together, with all steel should be painted at least two coats before erection. All 110 of the steel members of the framework are to be welded and riveted together before the placing of the timber members.

It will be seen that I provide a wooden ship with a steel sub-frame, so riveted and welded together that for all practical purposes it is a unit, and I thus provide continuity for the entire framework; also steel reinforcing is provided to meet all tension and torsional strains, so that the shock of 120 impact, or the vibration of the ship may be quickly distributed over a large area; and the wooden timbers of the frames act as shock absorbers, to minimize the effect at any particular portion of the hull.

I also reinforce the frames both transversely and longitudinally with steel, so 125 that the usual ceiling is not necessary, and

the frame and outer planking are accessible for easy repair, and are less subject to dry rot.

I also provide a high factor of safety for 5 all parts by utilizing longitudinal members to assist transverse members locally, and thus provide two ways of caring for the same local strains.

I also provide a method of beam fabrication which combines the use of common shapes of small steel sections, preferably of 10 T shape, with wooden members, connected together by bolts, so that both members of the compound beam will work together in 15 the proper relation of their moduli of elasticity, as though the whole were a unit of homogeneous material.

I also provide a system of ship construction that may be fabricated in the mill, and 20 set up largely by other skilled labor than shipwrights.

I also provide a system of ship construction which makes possible the building of 25 larger wooden ships with the same desirable qualities of strength, ease of handling, and ease of repair as with steel ships.

It will also be seen that the large proportion of wood in the structure will render 30 the vessel more buoyant when partly filled with water than with an all steel ship; and therefore better able to float with one or more compartments filled with water, as when the hull is perforated. Moreover, the 35 structure has much greater resistant power to torpedo attack than an all steel structure.

I do not mean to limit the invention to any precise proportion of parts or details of construction, except as specifically set out in the claims, as it will be obvious that 40 various modifications might be made by anyone skilled in the art, which could be used without departing from the spirit of my invention.

Having thus described my invention, 45 what I claim and desire to secure by Letters Patent of the United States is:—

1. A marine vessel having a steel framework comprising a series of T-beams connected together, wooden timbers secured to 50 the webs of said T-beams by bolts passing through said webs, and planking secured to said beams by bolts passing through the flanges of said T-beams and said timbers, substantially as described.

55 2. A marine vessel having a steel framework comprising a series of T-beams connected together vertically, transversely and longitudinally, wooden timbers secured to the webs of said T-beams by bolts passing 60 through said webs to form a single compound beam of wood and steel, and planking secured to said beams by bolts passing through the flanges of said T-beams and said timbers, substantially as described.

3. A marine vessel having a steel framework 65 comprising a series of T-beams connected together, wooden timbers secured to the webs of said T-beams by bolts passing through said webs, to form compound beams of wood and steel and planking secured to said beams by bolts passing through the flanges of said T-beams and said timbers, 70 with longitudinal and transverse bulkheads mounted between said beams and forming a multicellular structure, and diagonal bracing 75 let into the face of said bulkheads and connected to said compound beams, substantially as described.

4. A marine vessel having a steel framework 80 comprising a series of T-beams connected together vertically, transversely, and longitudinally, wooden timbers secured to the webs of said T-beams by bolts passing through said webs to form a single compound beam of wood and steel, and planking 85 secured to said beams by bolts passing through the flanges of said T-beams and said timbers, with longitudinal and transverse bulkheads mounted between said beams and forming a multicellular structure, and diagonal bracing let into the face of said bulkheads and connected to said compound beams, substantially as described. 90

5. A marine vessel having a steel framework 95 comprising a series of T-beams connected together, wooden timbers secured to the webs of said T-beams by bolts passing through said webs, and planking secured to said beams by bolts passing through the flanges of said T-beams and said timbers, 100 with longitudinal and transverse bulkheads mounted between said beams forming a multicellular structure, angle irons secured to said bulkheads and said beams at the joints between said bulkheads and said beams, and diagonal bracing connected to said angle irons and let into the face of said bulkheads, substantially as described. 105

6. A marine vessel having a steel framework 110 comprising a series of T-beams connected together vertically, transversely and longitudinally, wooden timbers secured to the webs of said T-beams by bolts passing through said webs to form a single compound beam of wood and steel, and planking 115 secured to said beams by bolts passing through the flanges of said T-beams and said timbers, with longitudinal and transverse bulkheads mounted between said beams forming a multicellular structure, angle irons secured to said bulkheads and said beams at the joints between said bulkheads and said beams, and diagonal bracing connected to said angle irons and let into the face of said bulkheads, substantially as described. 120

7. A marine vessel having a steel framework 125 comprising a series of T-beams con-

5 nected together, wooden timbers secured to the webs of said T-beams by bolts passing through said webs, and planking secured to said beams by bolts passing through the flanges of said T-beams and said timbers, with longitudinal and transverse bulkheads mounted between said beams forming a multicellular structure, angle irons secured to said bulkheads and said beams at the joints 10 between said bulkheads and said beams, and diagonal bracing connected to said angle irons and let into the face of said bulkheads, and other diagonal bracing crossing said inset bracing and secured on the 15 face of the bulkhead and also secured to said angle irons, substantially as described.

8. A marine vessel having a steel framework comprising a series of T-beams connected together, vertically, transversely and 20 longitudinally, wooden timbers secured to the webs of said T-beams by bolts passing through said webs to form a single compound beam of wood and steel, and planking secured to said beams by bolts passing through the flanges of said T-beams and said timbers, with longitudinal and transverse bulkheads mounted between said beams forming a multicellular structure, angle irons secured to 25 said bulkheads and said beams at the joints between said bulkheads and said beams, and diagonal bracing connected to said angle

30 irons and let into the face of said bulkheads, with other diagonal bracing crossing said inset bracing and secured on the face of the bulkhead and also secured to said angle 35 irons, substantially as described.

9. In a marine vessel, the combination with a series of frames each formed of a metal T-beam with a wooden timber on each side of and bolted to the web thereof, of planking bolted to said timbers and to the flanges of said T-beams, bolsters spanning a plurality of said frames and bolted to said frames, and transverse bulkheads secured to said bolsters, substantially as described. 45

10. In a marine vessel, the combination with a series of frames each formed of a metal T-beam with a wooden timber on each side of and bolted to the web thereof, of planking bolted to said timbers and to the flanges of said T-beams, bolsters spanning a plurality of said frames and bolted to said frames, and transverse bulkheads secured to said bolsters, diagonal bracing let into the 50 face of said bulkheads and connected to said bolsters, and other diagonal bracing crossing said inset bracing and secured on the face of the bulkheads and also secured to said bolsters, substantially as described. 55

In testimony whereof I affix my signature. 60

LUTHER STRINE MUNSON.
